SWITCH

Stanley R. Du Brie, Detroit, Mich.

Application May 23, 1935, Serial No. 22,974

4 Claims. (Cl. 200—83)

The switch disclosed in this application is of the pressure type and is characterized by its being made of stampings or the like.

For an understanding of the switch disclosed herein, the following specification should be read in connection with the appended drawings. In these drawings,

Figs. 1 and 2 are elevational views, with a cover removed, of the switch in on and off positions, respectively;

Fig. 3 is a view as if from the left of Fig. 1 with a binding post shield removed;

Fig. 4 is a view as if from the left of Fig. 2 with the shield in place;

Figs. 5, 6, 7, 8, and 9 are sections as if on lines 5—5, 6—6, 7—7, 8—8, and 9—9 of Figs. 1, 1, 2, 7, and 5, respectively;

Fig. 7a is a view like Fig. 7 but showing a modification.

Fig. 10 is a detailed view.

Referring to the drawings, it will be observed that the switch therein shown comprises a base plate 10 and a casing 11. Under the base plate, which is circular in form, but which has an apertured radially extending part 12 projecting therefrom, is a circular diaphragm 14 of rubber or the like, and immediately under this diaphragm is a chambered diaphragm plate 15. The base plate, the diaphragm, and the diaphragm plate are relatively secured in assembly to provide a pressure chamber by means of the series of bolts 16. Two of the bolts are passed through the base plate and lugs 18 of the casing walls to secure the casing to the base plate, and thus to secure the casing and the pressure chamber in assembly.

Disposed within the pressure chamber and above the diaphragm is a pressure plate (not shown) provided with an upwardly extending pin 20 engaging the horizontal arm of the pressure bell crank 22, the latter being pivotally mounted at 23. The vertical arm of the pressure crank is hooked over and has its upper end connected to the side wall of the casing by a coiled tension spring 25 and an adjusting bolt 26 threaded through a nut 27. The last mentioned parts provide a well-known means for bodily shifting the differential or range of openings or closing pressure limits of the switch, and adjustment of these parts for shifting the range is accomplished by movement of the nut 27 on the bolt 26.

The operating mechanism of the switch, as a whole, is connected to the pressure bell crank 22 through the horizontal arm 28 thereof, the latter having a hole 29 in which is the hooked upper end of the snap action spring 30 whose lower end

is secured to a threaded bolt or pin 32 which goes through a clear hole in the bight of a throw arm 33 and threads through an adjusting nut 34.

This construction provides an adjustment for increasing or decreasing the differential or operating range of the switch.

The free ends of the throw arm are notched at 35 to receive the notched lugs 36 of an anchor plate 37 welded to the casing 11 and thus form knife edge pivots for the throw arm.

A cross part 38 of the throw arm rides between a tongue 39 of a metal stamping riveted to an insulation contact carrying plate 40, and the stamping has bent-over tongues 41 disposed in slots of the anchor plate for pivotally suspending the plate 40.

The lower end of plate 40 is T-shaped and mounts stirrups 42 (Fig. 7) or is formed with seats 42a terminating in loops 42b (Fig. 7a) in which are double contact blades 43 whose contact tips 44 engage contact tips on stationary contacts 45 riveted to a doubly flanged insulation plate 46 mounted on the side wall of the casing 11 and having line and load binding posts 47. The blades 43, bridging contacts 45, float in the stirrups or loops and coiled springs 48 therein bias the blades against contacts 45; movement of blades 43 in the stirrups or loops 42 is guided by the blade notches 49 receiving sides of the stirrups or loops.

For limiting switch throw, throw arm 33 is formed with a lug 50 through whose tapped hole threads an adjustable screw 51 which engages a stop lug 52 welded to the casing 11, and this lug has a tapped hole 53 receiving a screw which holds a casing cover plate in place.

It will be observed that when the pressure bell crank 22 rocks clockwise on an increase in pressure, coil spring 30 will move over center with a snap action and such movement will cause the throw arm 33 and the contact plate 40 to move for quick break, from the position shown. Conversely, a decrease in pressure will cause the switch to close, if it had been opened, the over center arrangement providing quick make movement for the parts.

It is also observed that the movement and mounting of the movable contacts are such that these engage the fixed contacts with a wiping action, so desirable in switch action. Further, instead of both points 44 of a blade 43 making simultaneously, the upper ones make before the lower ones make; conversely, the lower contact points break before the upper contact points break.

In assembling switch parts, the tightening of screws 16 and the reaction of spring 30 pulls the throw arm ends into the notches of the lugs 36 of the anchor plate.

5 I claim:

1. In a pressure switch mechanism, a pressure bell crank mounted to rock on its pivot with variations in the controlling pressure, a throw arm in the form of a U strap straddling an arm of the pressure bell crank, an adjustably mounted coiled tension spring having its ends connected to and connecting the aforesaid arm of the pressure bell crank with the bight of the throw arm, the ends of the throw arm being pivotally connected to fixed structure through knife edge bearings, a contact carrying arm pivotally mounted on fixed structure, and having a slot in which rides a cross piece of the throw arm.

2. In a pressure switch mechanism, a pressure bell crank mounted to rock on its pivot with variations in the controlling pressure, a throw arm in the form of a U strap straddling an arm of the pressure bell crank, an adjustably mounted coiled tension spring having its ends connected to and connecting the aforesaid arm of the pressure bell crank with the bight of the throw arm, the ends of the throw arm being pivotally connected to fixed structure through knife edge bearings, a contact carrying arm pivotally mounted on fixed structure, and having a slot in which rides a cross

piece of the throw arm, and a stop on the throw arm for engaging fixed structure to limit the movement of the throw arm.

3. In a pressure switch mechanism, a fixed structure frame, a pressure bell crank pivotally mounted thereon to rock on its pivot with variations in the controlling pressure, a throw arm in the form of a U strap straddling an arm of the pressure bell crank, an adjustably mounted coiled tension spring having its ends connected to and connecting the aforesaid arm of the pressure bell crank with the bight of the throw arm, the ends of the throw arm being pivotally connected to the fixed structure frame through knife edge bearings, and a contact carrying arm pivotally mounted on the fixed structure frame, and operatively connected to the throw arm.

4. In pressure switch mechanism, a pressure bell crank mounted to rock on its pivot with variations in the controlling pressure and having a horizontally extending portion, vertical arms pivotally mounted at their upper ends on fixed pivots near the extension and operatively connected to each other between their ends so as to swing with each other in the same general direction, a coiled tension spring connecting the lower end of one arm with the extension, and contacts at the lower end of the other arm.

STANLEY R. DU BRIE. 30
